FINISHING MACHINE FOR LAUNDRY OR THE LIKE

David A. Freeman, 1600 Foster St., Evanston, Ill.

Filed Mar. 21, 1960, Ser. No. 59,809

Term of patent 14 years

(Cl. D49—1)

Fig. 1

Figure 1 is a front elevational view of a finishing machine for laundry or the like embodying my new design;
 Portions of the machine are shown broken away in Figures 3 and 4 for the convenience of illustration.

I claim:

The ornamental design for a finishing machine for laundry or the like, substantially as shown and described.
